UNITED STATES PATENT OFFICE.

MARTHA BANACH, OF NEW YORK, N. Y.

HAIR WAVER.

Application filed April 7, 1926. Serial No. 100,395.

This invention relates to a hair waver.

An object of the invention is to provide a simple and efficient apparatus whereby a double wave in the hair can be very readily produced with the expenditure of a minimum amount of time and labor on the part of the operator.

A further object concerns the provision of means whereby the matter of disposing the hair in the apparatus and removing it therefrom is much simplified, thereby cutting down the usual time of the operation.

The invention is illustrated in the drawings, of which—

15 Figure 1 is a perspective view of the hair-receiving plates mounted in the heating casing;

Figure 2 is a section on the line 2—2 of Figure 1;

20 Figure 3 is a perspective view of one of the hair-receiving plates;

Figure 4 is a front elevation of one of said plates with the hair disposed and fastened therein;

25 Figure 5 is a partial section on the line 5—5 of Figure 1.

The form of the invention shown in the drawings is a preferred form, although it is understood that modifications in the construction and arrangement of the parts and in the character of the materials used may be adopted without departing from the spirit of the invention as set forth in the appended claims.

35 In its general aspect the invention comprises a pair of corrugated plates, the dimensions of the corrugations corresponding to the dimensions or size of the waves to be produced in the hair. These plates are 40 adapted to be disposed adjacent each other with the hair properly clamped therebetween. These plates are then disposed in a hollow casing and resiliently held therewithin without the necessity of using a special locking or latching means, this casing having walls which are provided with suitable electrical heating units therein.

In the operation of the device it is merely necessary to properly dispose the hair on 45 one plate and then place the other plate thereover and slip the two plates into the heating casing, in which position they are held by suitable resilient means and then plug the wires of the heating casing into the proper socket to cause a transmission of heat to the hair. After the hair has been

properly treated the current is turned off and the plates are slid out of the casing and very readily separated, after which the hair can readily be removed from one of the 60 plates to which it is fastened.

In the preferred form of the invention I show a heating casing 10 having a hollow, central chamber 11. The heating casing has an outer wall 12 and an inner wall 13 within which a frame of insulation 14 is disposed and around this frame are wrapped electrical heating wires such as 15 which may, if desired, be insulated or covered with insulation. These wires are led out in the form of a cable 16 to be plugged into any desired connection. The hair is adapted to be gripped between corrugated plates such as 16 and 17. Corrugations of these plates are of the proper dimensions to give the desired size of wave or curl to the hair and at each end are provided with turned over flanges such as 18 and 19 on which spring members such as 20 are disposed. One of the plates is provided at the ends of each 80 groove with pins 21 which are adapted to project through suitable openings 22 formed in the other plate so that these two plates when placed together can be held in this aligned position. These pins also act as 85 means around which a flexible connector such as a strip of tape 23 can be passed, this tape acting to hold the hair 24 in position on the plate 16 after which the other plate is laid thereagainst.

90 It will be noted from Figure 4 that the hair is laid against the plate 16 and not only a vertical wave, due to the corrugations, is produced, but also a lateral wave, indicated by the numeral 25, which is produced by moving the hair laterally along the top, each corrugation thus giving a double wave effect. When the plates are placed together they are then slipped into the casing 10 the spring members 20 by 100 reason of their resiliency tending to hold the plates within the casing.

105 Preferably the hair has been treated in the usual manner with suitable liquids and after the current is turned on and the hair has been treated for the proper amount of time the plates can be easily slid out of the casing and merely pulled apart. By then unfastening the tape 23 the hair automatically becomes detached from the plate 16.

110 Thus I have provided a simple and efficient device which can be readily manipu-

lated to quickly and easily dispose the hair therein and remove it therefrom after the heating operation is over.

Preferably each of the plates 16 and 17 is provided on their adjacent facings with linings such as 26 and 27 which may be of cloth or other suitable fabric to keep the hair away from the metal of the plate.

What I claim is:

- 10 1. A hair waver which comprises a corrugated metal plate having longitudinal grooves, pins in opposite ends of each groove and a flexible tape adapted to connect longitudinally and laterally adjacent pins to hold the hair between the tape and the bottom of the groove.
- 15 2. A hair waver which comprises a pair of corrugated plates having alternate grooves and ribs which are adapted to be alined, said plates adapted to receive hair therebetween, said hair disposed transversely of the grooves to produce a wave therein, one of said plates having pins at the opposite ends of each groove and the other plate 25 having apertures in the opposite ends of the grooves to receive said pins whereby the plates can be held in alinement.
- 30 3. A hair waver which comprises a pair of corrugated plates having alternate grooves and ribs which are adapted to be

alined, said plates adapted to receive hair therebetween, said hair disposed transversely of the grooves to produce a wave therein, one of said plates having pins at the opposite ends of each groove and the other plate having apertures in the opposite ends of the grooves to receive said pins whereby the plates can be held in alinement, and a flexible tape adapted to extend from one pin to another in order to hold the hair in place on the plate.

4. A hair waver which comprises a pair of corrugated plates having alternate grooves and ribs which are adapted to be alined, said plates adapted to receive hair therebetween, said hair disposed transversely of the grooves to produce a wave therein, one of said plates having pins at the opposite ends of each groove and the other plate having apertures in the opposite ends of the grooves to receive said pins whereby all plates can be held in alinement, and a casing surrounding said plates, said casing also surrounding an electric heating element to heat said plates, and being provided with a heat insulating layer to reduce the heat radiation to the outside of said casing and to concentrate the heat upon said plates.

MARTHA BANACH.
